FIXTURE CONNECTER

Wesley Wilson, Chicago, Ill.

Application December 12, 1930, Serial No.
501,931. Renewed February 11, 1933

9 Claims. (Cl. 294—20)

This invention relates to apparatus for connecting and disconnecting electrical fixtures disengageably secured to a ceiling and has particular reference to apparatus for connecting and disconnecting a lighting fixture which has readily engageable and disengageable electrical and mechanical connector means, for connection with a ceiling unit.

An object of this invention is to provide a form of apparatus or tool and a form of fixture for cooperation therewith which will enable detachable ceiling lighting fixtures to be readily attached and detached, both mechanically and electrically, without the use of a step-ladder or the like.

Further objects and advantages will be apparent from the following description when taken together with the accompanying drawings, in which latter:

20. Figure 1 is a side elevational view, partly in section, of the apparatus embodying the present invention and a form of fixture adapted to be connected and disconnected thereby;

25. Fig. 2 is a top plan view taken substantially on line 2—2 of Figure 1;

Fig. 3 is a cross-sectional view of the insulating base taken on the line 3—3 of Fig. 2;

Fig. 4 is a top plan view of the bifurcated positioning end of the guide member; and

30. Fig. 5 is a top plan view of the carrier arm for gripping the fixture to connect and disconnect the same.

Referring more particularly to the drawings, there is shown a ceiling unit 1, comprising an upper housing or canopy member 2 in the lower portion of which is positioned a substantially cup-shaped insulating base 3 having a central tapered slotted opening 4 in the bottom thereof. Wiring terminals 5 are positioned within the insulating base 3, to which the lead wires 6 are connected. The wiring terminals 5 are electrically connected to and position the contacts 7, which are preferably spring contacts extending within the insulating base 3. The slot 4 has shoulder portions 8 on each side thereof, which are adapted to support a lighting fixture assembly, as will be hereinafter described. A lower housing 9 is engageable with the lower end of the upper housing 2 extending downwardly some distance therefrom, and is provided with a central opening 10 in the bottom thereof.

55. A plate member 11, which is also provided with a central opening therein, is positioned above the lower housing 9.

The upper housing 2 is preferably formed with a reduced neck portion 12.

A lighting unit assembly is attached to the lower end of a hollow stem 13 and comprises the hood 14 in which is mounted a lamp receptacle, a reflector 15, and a globe 16. It is to be understood that the lighting fixture assembly is herein described merely for the purposes of illustration, as any other form desired may be employed equally well.

The stem 13 extends through the central openings in the lower housing member 9 and the plate 11, which openings are vertically aligned. A horizontal supporting member or cross-head 17 is secured to the upper end of the stem 13. The ends of the supporting member 17 are formed on a bias so as to taper inwardly toward the bottom, as shown in Fig. 1. The supporting member 17, when in the position shown in Fig. 1, rests on the shoulder portions 8, and thereby supports the lighting unit assembly. The width of the supporting member is less than the width of the slot 4 so that the supporting member may pass through the slots hereinbefore mentioned, which is done in attaching or detaching the lighting unit assembly from the ceiling unit.

In making the connection, the cross-head 17 is lined up with the flaring entrance to the slot 4, the fixture stem 13 is pushed upwardly until the ends of the cross-head are above the level of the raised bosses 17a and the fixture stem is then given a quarter turn clockwise, as seen in Fig. 2, to bring the ends of the cross-head into registration with the spring contacts 7. The fixture stem is then allowed to drop down into the pockets in which the contacts 7 are located, thus establishing a reliable mechanical and electrical connection between the fixture and the ceiling unit. In making the connection, the plate 11 engages the lower face of the ceiling unit and as the fixture stem is pushed upwardly, the spring 20 is compressed between the plate 11 and the shoulder 19. This spring tends to urge the stem downwardly, thus holding the contacts 18 on the cross-head 17 in engagement with the contacts 7 on the ceiling unit.

It has been found preferable to employ a ball joint 21 between the hood 14 and the lower end of the stem. With this construction, the connection between the ceiling unit and the lighting unit assembly will not be affected by any jarring of the lighting unit assembly.

Attached to the stem 13 above the ball joint 21 is a collar portion 22, which is preferably formed with a corrugated or fluted surface so that

it may be easily gripped for rotating the stem to connect or disconnect the lighting unit assembly from the ceiling unit.

For attaching or detaching the lighting fixture above described, or any other fixture having electrical or mechanical connector means, the following apparatus may be employed. This apparatus comprises a guide member 23 having a vertical handle portion 24 and a horizontal posit-

10 tioning portion 25.

The positioning portion 25 comprises a pair of spaced arms 26 between which is pivotally mounted a yoke member 27 which, when in position, straddles the neck portion 12 of the ceiling unit.

15 This yoke member is provided with a pair of rollers 28 having vertical axes for engagement with the side of the enlarged cylindrical lower portion of the ceiling unit, a set of three anti-friction rollers 29 mounted on horizontal pivot 20 pins and engaging the flat horizontal annular surface between the neck portion and the cylindrical portion, and a pair of rollers 30 having vertical axes and engaging the reduced neck portion 12 of the ceiling unit. The pivotal connection 25 of the arms 26 with the yoke permits similar movement of the handle portion 24 without disturbing the engagement of the rollers on the yoke with the ceiling unit.

With this construction, the yoke 27 may be 30 slipped about the neck portion 12 of the ceiling unit and dropped down so that the pair of rollers 28 engage the sides of the cylindrical lower portion of the ceiling unit, the set of three rollers 29 resting on the horizontal annular surface so that 35 the guide member as a unit may be easily rotated or swiveled about the ceiling unit without any danger of its becoming disconnected or getting out of adjustment. This swiveling movement is for use in effecting a quarter turn of the fixture 40 for connecting it and disconnecting it with respect to the ceiling unit, as explained more in detail hereinafter.

A pulley 31 is mounted in the upper end of the handle 24 of the guide member 23, and a cleat 45 32, preferably of the spring variety, is fastened to the lower outer side of the handle portion 24.

A fixture carrier comprising an arm 33 having an opening 34 therein through which the handle 24 extends is adapted to slide up and down on 50 the handle 24. The handle 24 of the guide member is preferably made square or non-circular, and the opening 34 in the arm 33 is similarly shaped so that the arm cannot rotate with reference to the guide member. Three wheels 35, 36 55 and 37 are mounted on the arm 33 so that the same will roll up and down the handle 24 of the guide member 23, the wheels 35 and 36 being positioned on the front and rear sides of the handle 24, and the wheel 37 being mounted on the down- 60 wardly extending portion 38 of the arm 33. A rope or cable 39 is fastened at one end to the ear portion 40 on the upper side of the arm 33 and extends over the pulley 31; thence downward through an opening 41, which is adjacent 65 the outer end of the arm 33, and is then fastened at the lower end to the cleat 32.

The outer end of the carrier arm 33 is bifurcated as at 42 so as to fit over the collar portion 22 on the stem 13 and engage the same in the 70 manner of a wrench to enable the stem to be turned about its axis in connecting and disconnecting the fixture. The apparatus above described is used to disconnect the lighting fixture as follows:

75 The positioning portion 25 of the guide mem-

ber 23 is positioned over the neck portion 12 of the upper housing member, the carrier arm 33 having been previously raised by means of the rope 39 above the lighting unit assembly. It is then positioned so that the bifurcated portion 42 engages the collar 22 on the stem 13. The cable 39 is then operated to lift the cross-head 17 out of engagement with the pockets in which the contacts 7 are located. By rotating the guide member 23 through a 90° arc, the supporting portion 17 is positioned parallel to the slot 4, after which the whole lighting unit assembly may be lowered by gradually easing the lower end of the rope 39, as the weight of the carrier arm and the lighting unit assembly will be sufficient to cause the carrier arm to slide down the handle 24.

In reassembling the lighting fixture with respect to the ceiling unit, a reverse series of operations is necessary. The fixture carrier 33 being in its lowered position and the forked portions 26 being properly positioned with respect to the ceiling unit, the collar portion 22 is placed in position in the seat formed by the bifurcations 42, the cable 39 is operated to elevate the fixture into proximity with the ceiling unit, and the handle 24 is swiveled about the ceiling unit to bring the cross-head 17 into alignment with the flaring entrance to the slot 4. The fixture stem is then given a slight additional upward lift to 105 bring the cross-head above the level of the bosses 17a, the handle 24 is then swiveled through a quarter turn to bring the ends of the cross-head into registration with the pockets in which the contacts 7 are seated, and the carrier is then lowered to permit the contacts 18 to engage the contacts 7 and to disengage the seat 42 from the collar 22. The handle 24 is then disengaged from the ceiling unit, leaving the fixture in assembled and connected relation with respect to 110 the ceiling unit.

By the construction shown and described, a detachable lighting fixture may be easily and quickly removed from its ceiling unit without the use of a step-ladder or the like, thus saving time 115 and energy in the operation.

While I have shown and described but one embodiment of the present invention, it will be apparent to those skilled in the art that various modifications thereof may be made without departing from the spirit and scope of the invention, and therefore I wish to be limited only by the prior art and the scope of the appended claims.

I claim:

1. Apparatus for connecting and disconnecting a lighting fixture (having readily engageable and disengageable mechanical connector means) with respect to an elevated connector unit placed at such a height that the fixture when connected is out of reach of the operator (having readily engageable and disengageable mechanical connector means) comprising a guide member provided with means for positioning it with respect to the elevated unit, and a fixture carrier guided by said guide member to bring the connector means on the fixture into operative engagement with the connector means on the elevated unit, said fixture carrier having sufficient movement with respect to said guide member to enable the carrier to lower the fixture carried thereby from its connected position to a position in which the operator standing on the floor can handle the fixture.

2. Apparatus for connecting and disconnect-

at such a height that the fixture when connected is out of reach of the operator (having readily engageable and disengageable mechanical connector means) comprising an anchorage member provided with means for positioning it with respect to the elevated unit, and a fixture carrier supported by said anchorage member for bringing the connector means on the fixture into oper-

ative engagement with the connector means on the elevated unit, said fixture carrier having sufficient movement with respect to the anchorage member to enable the carrier to lower the fixture carried thereby from its connected position to a position in which the operator standing below can handle the fixture. 30
